DESIGN FOR A GARMENT MEASURING BOARD

Phil C. Bowen, Kansas City, Mo.

Application March 3, 1941, Serial No. 99,289

Term of patent 3½ years

To all whom it may concern:

Be it known that I, Phil C. Bowen, a citizen of the United States, residing at Kansas City, in the county of Jackson and State of Missouri, have invented a new, original, and ornamental Design for a Garment Measuring Board, of which the following is a specification, reference being had to the accompanying drawing, forming a part thereof.

Fig. 1 is a front elevational view of the garment measuring board, showing my design; and Fig. 2 is an edge elevational view thereof.

I claim:

The ornamental design for a garment measuring board, as shown.

PHIL C. BOWEN.
